No. 829,136.

PATENTED AUG. 21, 1906.

S. H. BLODGETT.
SAFETY ATTACHMENT FOR GAS BURNERS.
APPLICATION FILED APR. 18, 1905.

THE NORRIS PETERS CO., WASHINGTON, D.C.

UNITED STATES PATENT OFFICE.

STEPHEN H. BLODGETT, OF SOUTH LINCOLN, MASSACHUSETTS.

SAFETY ATTACHMENT FOR GAS-BURNERS.

No. 829,136.

Specification of Letters Patent.

Patented Aug. 21, 1906.

Application filed April 18, 1905. Serial No. 256,241.

To all whom it may concern:

Be it known that I, STEPHEN H. BLODGETT, a citizen of the United States, residing in South Lincoln, county of Middlesex, and State of Massachusetts, have invented an Improvement in Safety Attachments for Gas-Burners, of which the following description, in connection with the accompanying drawings, is a specification, like letters and numerals on the drawings representing like parts.

This invention relates to a safety gas-burner of the class wherein provision is made for automatically shutting off the supply of gas when the gas ceases to burn.

The invention is especially adapted to be applied to gas-burners employing a mantle—such, for instance, as the Welsbach burner.

In accordance with this invention the gas-supply pipe is provided with a valve having coöperating with it a device for automatically closing the valve, which device is moved into its operative position when the valve is opened and is retained therein by a thermostatic device located above said valve in the heating zone of the Welsbach burner. The thermostatic device is provided with a member which is moved longitudinally in one direction by the heat of the burner and is moved longitudinally in the opposite direction when the burner cools.

These and other features of this invention will be pointed out in the claims at the end of this specification.

Figure 1 is an elevation of a Welsbach gas-burner provided with a safety device embodying this invention, the parts being shown in the position they occupy when the valve is closed; Fig. 2, a side elevation, on a smaller scale, of parts shown in Fig. 1 looking toward the left; Fig. 3, a side elevation showing the gas cock or valve in its open position; Figs. 4 and 5, details in side elevation to be referred to; and Fig. 6, a detail, on an enlarged scale, to be referred to.

Referring to the drawings, *a* represents a fitting provided with a gas-outlet tip or pipe *b*, upon which is fitted a Welsbach burner *c*, having a mantle *d*, all of which parts are or may be of any suitable or desired construction.

The fitting *a* is provided with a cock or valve *e*, having a handle or thumb-piece *f*, and upon which is loosely mounted a sleeve *g*, having an arm *h*, said sleeve being adapted to be moved in one direction with the valve *e*

when the latter is turned into its open position and to be moved in the opposite direction to close the valve by a coiled spring *i*, as will be described. The arm *h* coöperates with two fingers *j* *k* on a thermostatically-operated device, shown in the present instance as a bar or piece *m*, said fingers being separated and arranged out of line with each other. The finger *j* is beveled or inclined to permit the arm *h*, which is also beveled at its upper end, to pass between said fingers and behind the finger *k*, by which it is engaged and prevented from being moved backward while the gas is being lighted at the burner *c*. The finger-carrying piece or bar *m* in the present instance is attached to or forms part of a metal piece or bar *n*, forked at its upper and lower ends to encircle an upright rod *p*, fastened at its lower end to a bar or plate *q*, projecting from the fitting *a* above the valve *e*. The rod *p* is extended longitudinally of the burner *c* and up into the heating zone of the same and preferably outside the mantle *d* thereof and has fitted over it a metal tube 10, preferably brass, which is fastened at its upper end to the rod *p* and has its lower end in engagement with the finger-carrying piece *n*.

The tube 10 constitutes a thermostat which when heated expands longitudinally and forces the bar *n* downward against the plate *q*, thereby springing or bowing out the bar *m* and moving the locking-finger *j* into the path of movement of the arm *h*, thereby preventing the said arm from returning to its starting position until the thermostatic tube has returned to its normal position, which takes place when the flame at the Welsbach burner is extinguished.

In operation with the apparatus herein shown the valve *e* is first turned from its closed position (shown in Figs. 1 and 2) into its open position. (Shown in Fig. 3.) During this movement of the valve the safety device or arm *h* is brought behind the finger *k*, (see Fig. 4,) which serves to hold it against the action of the spring *i*. The gas is then lighted and the heat from the Welsbach burner expands the thermostatic tube 10 and moves the finger piece or bar *m* so as to remove the finger *k* from engagement with the arm *h* and bring the finger *j* into the path of movement of said arm, which latter is moved by the spring *i* into engagement with the finger *j*. (See Fig. 5.) While the arm *h* is thus held, the valve *e* may be partially closed without

disengaging the arm from the finger, so that the gas may be turned down. If for any reason the burner-flame should be extinguished—as, for instance, by being accidentally blown out or by the pressure of the gas falling below a predetermined point—the thermostatic tube or rod 10 is moved longitudinally upward, thereby removing the finger *j* from engagement with the arm *h* and permitting the 5 spring *i* to turn the sleeve *g* and its attached arm back into its starting position. (Represented in Fig. 2.) If the valve *e* should be either wholly or partially opened, it will be carried back into its closed position by the sleeve 10 *g*, which in the present instance is provided with a lug or projection 20, which extends into the path of movement of a projection or device 21 on the valve *e*. The sleeve *g* is turned to cause the arm *h* to engage the fingers *j* *k* when the valve is opened by the projection 21 on the valve engaging the projection 20 on the sleeve.

I claim—

1. The combination with a gas-burner provided with a mantle and with a valve controlling the flow of gas to said burner, of a sleeve loose on said valve, an arm on said sleeve, means on said valve coöperating with means on said sleeve to move said sleeve and arm when the valve is opened and to permit said valve to be partially closed independently of said arm, a finger-carrying piece movable toward and from said arm in a substantially vertical plane, and a thermostat located in the heating zone of the burner and connected with said finger-carrying piece to effect movement of said finger-carrying piece in a substantially vertical plane in one direction, substantially as described.

2. The combination with a gas-burner provided with a mantle and with a valve controlling the flow of gas to said burner, of a sleeve loose on said valve, an arm on said sleeve, means on said valve coöperating with means on said sleeve to move said sleeve and arm when the valve is opened and to permit said valve to be partially closed independently of said arm, a finger-carrying piece movable toward and from said arm in a substantially vertical plane, and a thermostatic tube having one end free and engaging the said finger-carrying piece and having its other end extended into the heating zone of the mantle and fastened against movement, substantially as described.

3. The combination with a gas-burner provided with a mantle and with a valve controlling the flow of gas to said burner, a device coöperating with said valve to be moved thereby when the valve is opened and to move the valve into its closed position, means to engage said device and retain it from acting to close said valve while the burner is lighted, and a longitudinally - movable rod having one end anchored in the heating zone

of the mantle and its other end free to move and operate said retaining means, substantially as described.

4. The combination with a gas-burner provided with a mantle and with a valve controlling the flow of gas to said burner, a device coöperating with said valve to be moved thereby when the valve is opened and to move the valve into its closed position, means to engage said device and retain it from acting to close said valve while the burner is lighted, and a longitudinally-movable rod having one end extended into the heating zone of the burner and its other end coöperating with the said retaining means to engage said means with said device when the burner is lighted, substantially as described.

5. The combination with a fitting provided with a gas-outlet pipe, a burner fitted upon said gas-outlet pipe and provided with a mantle, a valve in said fitting to control the supply of gas to the said burner, a safety device coöperating with said valve to close the same, a thermostat located above the said valve within the heating zone of the said burner, and means located in proximity to the valve to control said safety device and actuated by the said thermostat when the burner is lighted to engage said safety device, substantially as described.

6. The combination with a gas - burner provided with a mantle, a valve controlling the flow of gas to said burner, a safety device coöperating with said valve to close the same, a thermostat located in the heating zone of the mantle, and means movable longitudinally of the burner and coöperating with said thermostat and with said device to prevent the latter from closing the valve while the burner is lighted, substantially as described.

7. The combination with a gas-burner, of a valve controlling the flow of gas to said burner, a safety device coöperating with said valve to close the same, a thermostat located in the heating zone of the burner, and a longitudinally - movable device separate from the thermostat and interposed between said thermostat and said safety device and controlling the operation of the latter, substantially as described.

8. The combination with a gas-burner, of a valve controlling the flow of gas to said burner, a safety device coöperating with said valve to close the same, a longitudinally-movable rod having one end anchored within the heating zone of the burner and having its other end extended to near said valve, and means interposed between the said rod and said safety device and actuated by said thermostat when the burner is lighted, substantially as described.

9. The combination with a gas-burner, of a valve controlling the flow of gas to said burner, a safety device coöperating with said

valve to close the same, a thermostatic tube having one end anchored in the heating zone of the burner and its other end free, and means interposed between said free end of 5 the tube and said safety device and actuated by said thermostat when the burner is lighted, substantially as described.

10. The combination with a gas-burner provided with a mantle and with a valve controlling the flow of gas to said burner, of a safety device coöperating with said valve to close the same, a thermostat located in the proximity to the mantle, and means located

in proximity to the valve and controlling the operation of said safety device, said means 15 being operated by said thermostat when the gas is lighted to engage said safety device, substantially as described.

In testimony whereof I have signed my name to this specification in the presence of 20 two subscribing witnesses.
